E. CROUSE

AIR VALVE

Filed Nov. 18, 1922

UNITED STATES PATENT OFFICE.

EMORY CROUSE, OF WICHITA, KANSAS.

AIR VALVE.

Application filed November 18, 1922. Serial No. 601,694.

To all whom it may concern:

Be it known that I, EMORY CROUSE, a citizen of the United States, residing at Wichita, in the county of Sedgwick and 5 State of Kansas, have invented certain new and useful Improvements in Air Valves; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to automatic liquid dispensing systems and relates more particularly to an improvement in valves for use in controlling the air by which the liquid is raised from the storage reservoir to the 20 graduated measuring bowl.

It is becoming increasingly common today to dispense liquid fuel by means of an apparatus which requires the fuel to be elevated into a transparent graduated measuring 25 bowl that is raised a considerable distance above the level of the ground. In elevating the liquid fuel, it is common to employ pumps or air pressure. In my co-pending application, Serial Number 529,773, filed 30 January 16, 1922, I have shown and described a liquid dispensing system in which compressed air is employed as the means for elevating the liquid fuel to the measuring bowl. In this system there is employed a 35 three-way valve, by means of which the compressed air can be directed into the auxiliary underground tank for the purpose of applying a pressure to the fuel which will cause it to flow upwardly into the measuring bowl, and which will also open the pipe to the atmosphere so as to permit the air to exhaust from the tank. My present invention is 40 directed to an improvement in valves of the type referred to above.

45 In order to more clearly describe my invention, I shall have reference to the accompanying drawing, in which—

Fig. 1 shows a side elevation of a dispensing apparatus, part of the casing being removed to show the arrangement of the pipes and the position of the valve.

Fig. 2 is a vertical section of my improved valve.

Fig. 3 is a side elevation of my valve with parts thereof broken away.

Fig. 4 is a transverse section taken on line 4—4, Fig. 2.

Fig. 5 is a transverse section taken on line 5—5, Fig. 2.

Fig. 6 is a transverse section taken on line 6—6, Fig. 2.

Fig. 7 is a side elevation of a portion of my valve; and

Fig. 8 is an elevation of another portion of my valve.

The same reference characters will be employed to designate the same parts throughout the several views.

In Fig. 1 I have shown a line 1, which represents the ground level below which is 70 located a main reservoir, which I have shown in dotted lines and designated by numeral 2. An auxiliary tank 3 is connected to the bottom of tank 2 by means of a pipe 4 having a check valve 5, which opens towards the 75 auxiliary tank. A pipe 6 extends from the bottom of tank 3 to the measuring bowl 7. A pipe 8 connects a supply of compressed air (not shown) to the lower end 9 of my improved air valve, which I shall designate 80 as a whole by the letter "V". A common globe valve 10 is provided in pipe 8 near valve V for the purpose of cutting off the air supply in case repairs become necessary. Valve V consists of a part 9 which has a 85 threaded opening 11 at its lower end and a pair of inwardly projecting lugs 12, which serve as stops for a valve member in a manner which will presently be explained. Part 9 is provided near its upper end with an 90 annular shoulder 13 which co-operates with the downwardly projecting flange 14 of part 15 for the purpose of clamping in place a flexible diaphragm 16, which serves to hold the valve member in place. Parts 9 and 15 95 are each provided with lugs 17, which are perforated for the reception of bolts 18 by means of which the parts are fastened together and the diaphragm 16 clamped between them. The diaphragm 16 has a central opening through which extends the cylindrical portion or valve member 19 whose upper end is threaded as indicated by numeral 20 and co-acts with a correspondingly threaded opening in a complementary member 21. At the lower end of cylindrical member 19 is a flange 22 which co-operates with the flexible member 16 to form a seal when the valve is inoperative. A central axial opening 23 extends downwardly from 110

105

110

the top of member 21 to a point near the bottom of valve member 19. Transverse holes 24 connect the central opening 23 with the exterior of member 19 and serve as a means 5 for enabling the air to enter this opening when the parts occupy the position shown in Fig. 3. Member 21 has an annular channel 25 in its upper end and within which 1 place leather or composition washers 26, 10 the purpose of which will appear as the description proceeds. It will be readily apparent from an inspection of Fig. 2 that if air under pressure is admitted to the interior of member 9 it will act upon the lower 15 surface of member 19 and flange 22 and force the same against the diaphragm 16 and cause a seal to be formed. If the parts 19 and 21 are forced downwardly until the flange 22 engages the upper surfaces of lugs 20 12 (Fig. 3) the transverse openings 24 will be moved to a position below diaphragm 16 and the air will flow through openings 24 into and out of openings 23. Member 15 has an upwardly extending portion 27 which 25 has a slight enlargement 28 at its upper end. An annular shoulder 29 is formed on the inside of part 28 and serves as a seat for the lower end of a spring 30. A tubular member 31 carries on its upper end an elbow 32 which 30 is provided with an upwardly extending ear 33. The tubular member 31 projects through the opening in part 27 and has its lower end formed of such size that it fits within the annular channel 25. The spring 35 30 abuts its ends against shoulder 29 and the lower edge of elbow 32 in the manner clearly shown in Figs. 2 and 3 and tends to hold the several parts in the position shown in Fig. 2. The member 15 is provided with 40 an opening 34 on one side for the reception of the exhaust pipe 35. The opening 36 in elbow 32 is connected by means of a flexible connection 37 with the pipe 38 which connects with the top of the auxiliary tank 3. 45 A lever 39 is pivoted at 40 to a support 41 and is joined to the ear 33 by a connecting rod 42 in such a manner that when the lever 39 is moved to the left about its pivot (see Fig. 1) the rod 42 will force the tubular member 31 downwardly against the washers 26 until the parts assume the position shown 50 in Fig. 3. Lever 39 will be held in valve open position by means of a latch 43 and is automatically released when the bowl 7 becomes full. It is evident that when the parts 55 occupy the position shown in Fig. 3, air from the compressed air supply will flow through pipe 8 through holes 24 into opening 23 and thence through tubular member 31 and elbow 32 into pipe 38 and to auxiliary tank 3. The air pressure acting upon the liquid in tank 3 causes the same to flow into the measuring bowl 7. When the latter becomes filled to the desired level the liquid 60 overflows into pipe 44 and releases the latch 65

43, thus permitting spring 30 to move the tubular member 31 into the position shown in Fig. 2. This allows parts 19 and 21 to move upward and close the valve, and it also establishes a passage from tank 3 to exhaust pipe 38, which permits the air to exhaust from tank 3 and permits the latter to fill again from tank 2. The means by which the overflow from bowl 7 causes the latch 43 to release, forms no part of my present invention, but an example of such a mechanism is shown and described in my co-pending application above identified. 75

My improved valve may be operated by hand when the automatic releasing means is 80 not made a part of the dispensing apparatus. In this case, the operator must obviously hold the valve in operative position while the measuring bowl is filled or else release the latch 43 when the bowl is full. 85

I have described my valve as provided with a spring 30 to hold the tubular member 31 in inoperative position, but I have also shown a weight W attached to the end of lever 40 for the purpose of operating the tubular member 31 in case the spring 30 breaks. The weight W may be depended upon entirely to move the tubular member 31 and when this is found desirable, the spring 30 may be omitted. 95

I want to call attention to the fact that valve 10 in addition to the use specified above, also serves as a regulating valve and is normally opened just enough to produce the required flow of air to raise the gasoline with a gentle flow as distinguished from the violent flow that would take place if the full air pressure was impressed upon the liquid. 100

It will be apparent, from the above description, taken in connection with the accompanying drawing, that I have invented a simple and substantial valve that is particularly well suited for the purpose under consideration. My valve has a few moving 105 parts and is so constructed that it is normally sealed or leakproof. When the valve is opened, tubular member 31 is in place to conduct the air to pipe 38 and when the valve is closed tubular member 31 is in direct 110 communication with pipe 35 so as to permit free exhaust from tank 3. Pipe 35 can be extended to any suitable place, preferably to tank 2, so that no inflammable gases will 115 be exhausted near the apparatus. 120

Having now described my invention, what I claim is:

1. A control device for use in liquid dispensing systems, comprising a hollow member having means at one end for attaching 125 a pipe thereto, an annular shoulder near the other end, a plurality of inwardly projecting stop members intermediate said first named end and said shoulder, a tubular member having a portion thereof projecting 130

into the hollow member and co-operating with the annular shoulder for the purpose of clamping a diaphragm in place, a diaphragm having a central opening clamped 5 between said shoulder and said tubular member, a two part valve member in the opening in the diaphragm longitudinally movable therein and adapted to engage said stop members when moved to open position, 10 one of said valve member parts having a circular channel at one end, resilient material in said channel, said valve member having an axial opening therein and a transverse opening extending from one end of 15 said axial opening to the outside of said valve member.

2. An air control device comprising a hollow member having means at one end adapted to be connected to a source of compressed 20 air, a valve mechanism adapted to normally prevent the compressed air from flowing out, a tubular housing surrounding the upper end of said valve mechanism, a tubular member slidably connected with said housing 25 said tubular member being normally spaced from but movable into contact with said valve mechanism to open the same and permit air to flow, the valve mechanism having an opening registering with the opening 30 in the tubular member for directing the air into the tubular member when the valve mechanism is open, said housing having an exhaust opening in one side thereof.

3. An air control device comprising a pair 35 of hollow members adapted to be connected together, a diaphragm extending transversely of said members, means for clamping said diaphragm firmly in place between said members, said diaphragm having a central opening therein, a cylindrical valve member, having a flange at one end and a threaded portion at the other end, said valve member extending through the central opening in the diaphragm, an opening extending 40 transversely through said valve member intermediate the flange and the threaded end and an axial opening extending from one end of said valve member and communicating with said transverse opening 45 a second member having a threaded opening adapted to co-operate with the threaded end of the first mentioned member, an axial opening extending through the second mentioned transverse member and communicating with the axial opening in the first mentioned member, a cylindrical channel in the end of the second mentioned member, a resilient washer in said channel, a tubular member slidably mounted in one of 50 said hollow members and adapted to engage the resilient washer in the circular channel, and means comprising a spring for normally maintaining the tubular member out of contact with said resilient washer.

4. An air control device for liquid fuel dispensing apparatus comprising in combination a pair of hollow members, one of said members having one end adapted to be connected to a source of compressed air supply, the other end thereof being provided 65 with a circular shoulder, the other hollow member having an end portion adapted to co-operate with the said shoulder to clamp a diaphragm in place, a circular diaphragm having its outer edges located between said 70 end portion and said shoulder, means co-operating with said hollow members to hold the same together and for clamping the diaphragm in place between said members, a cylindrical valve member passing through 75 an opening centrally of said diaphragm, a flange on one end of said valve member, a threaded portion on the other end, a transverse opening through the cylindrical member at a point intermediate the flange and 80 the threaded portion, a second member having a threaded opening adapted to co-operate with the threaded end of the first mentioned member, a circular channel in the end of the second member, a resilient washer in 85 said channel, an axial opening extending from the transverse opening to the outer end of the second member and a tubular member adapted to engage said washer and move the valve to open position. 90

5. An air control device comprising a pair of hollow members adapted to be connected together, a diaphragm extending transversely of said members, means for clamping said diaphragm firmly in place between 100 said members, said diaphragm having a central opening therein, a cylindrical valve member, having a flange at one end and a threaded portion at the other end, said valve member extending through the central opening in the diaphragm, an opening extending transversely through said valve member intermediate the flange and the threaded end and an axial opening extending from one 105 end of said valve member and communicating with said transverse opening a second member having a threaded opening adapted to co-operate with the threaded end of the first mentioned member, an axial opening extending through the second mentioned 110 member and communicating with the axial opening in the first mentioned member, a cylindrical channel in the end of the second mentioned member, a resilient washer in said channel, a tubular member slidably mounted in one of said hollow members and adapted to engage the resilient washer in the circular channel, and means for normally maintaining the tubular member out of contact with said resilient washer. 115

In testimony whereof I affix my signature.

EMORY CROUSE.
